CLAIM

An ornamental design for a mosquito clamp and needle holder, as shown and described.

DESCRIPTION

FIG. 1 is a perspective of a first embodiment of a mosquito clamp and needle holder;

FIG. 2 is a top view of the mosquito clamp and needle holder shown in FIG. 1;

FIG. 3 is a bottom view of the mosquito clamp and needle holder;

FIG. 4 is a left side view of the mosquito clamp and needle holder;

FIG. 5 is a right side view of the mosquito clamp and needle holder;

FIG. 6 is a front view of the mosquito clamp and needle holder; and,

FIG. 7 is a rear view of the mosquito clamp and needle holder.

The broken line showing in FIGS. 1, 2 and 3 are for illustrative purposes only and forms no part of the claimed design.
